MINING MACHINE

Frederick B. Miller, Chicago, Ill.

Application June 14, 1946, Serial No. 676,662

19 Claims. (Cl. 262—12)

1

This invention relates to a coal mining machine adapted to undercut the coal, wedge down the coal undercut and load the coal cuttings from the undercut and the coal wedged down over the undercut.

An object of the invention is to provide a coal mining machine with a novel arrangement of hydraulic cylinders controlled by a novel arrangement of valves capable of positioning and reciprocating a wedge plate for breaking down successive portions of coal above the kerfs cut by the machine.

Another object is to provide such a machine with a reciprocating wedge plate capable of being adjusted for breaking down successive portions of coal to a predetermined height.

A further object is to provide a coal mining machine with a reciprocating wedge plate capable of being adjusted for breaking down successive portions of coal in various sizes.

A further object is to provide a coal mining machine as above described which will incorporate a wedge plate adapted to be reciprocated by the pressure cylinder supplied with fluid under pressure and provided with a resilient anchor for decelerating the wedge plate at the end of the return stroke and which will additionally absorb the shock imposed in starting and accelerating the wedge plate on a forward stroke, the said pressure cylinder being supplied with fluid under pressure from a fixed displacement pump.

These and other objects will be apparent after referring to the accompanying drawings in which:

Figure 1 is a plan view showing an arrangement of cylinders and valves for positioning and reciprocating the wedge plate mounted on the machine for breaking down the coal and also showing the means for undercutting the coal and conveying the coal mined.

Figure 2 is a side elevational view of the machine taken on line II—II of Figure 1, showing the cylinders, valves and piping in relation to the wedge plate, also showing the means for moving the machine forward for undercutting the coal, and means for moving the mined coal away from the working face.

Figure 3 is an enlarged longitudinal sectional elevational view taken on line III—III of Figure 1, showing the arrangements of the valves and piping and also showing the resilient means for anchoring the cylinder that reciprocates the wedge plate.

Figure 4 is an enlarged longitudinal sectional elevational view taken on line IV—IV of Figure 1, showing the arrangement of the cylinders and the

2

piping and also showing the rotary cutter bar and the wedge plate in relation to the coal to be mined.

Figure 5 is a transverse sectional view taken on line V—V of Figure 1.

Figure 6 is a fragmentary sectional view taken on line VI—VI of Figure 5.

Figure 7 is a fragmentary cross sectional view taken on line VII—VII of Figure 6.

Figure 8 is an enlarged sectional view of the selective valves.

Figure 9 is an enlarged sectional view of the control valve.

Figure 10 is an enlarged sectional view of the pressure valve.

Figure 11 is an enlarged sectional view of the check valve.

Figure 12 is an enlarged sectional view of the relief valve.

20 In carrying out that part of my invention pertaining to the apparatus for automatically reciprocating and swinging the wedge plate for breaking down successive portions of the coal above previously cut kerfs, I use the undercutting means like that shown and described in my prior United States Patent No. 2,368,863, dated February 6, 1945, comprising a main frame 10 slidably mounted on the anchored skid base 11. A skid base cylinder 12, mounted in the main frame 10, is provided with a piston 13 fixed to a piston rod 14 connected to the skid base 11 with a pin 15. Forwardly of the main frame 10 is a portion in the form of a base 16, in which a feeder plate 17 is reciprocally mounted. Integral with the feeder plate 17 is a pair of spaced lugs 18 between which is mounted a roller 19 journalled on the pin 20. Against the lug 21, integral with the underside of the base 16, is seated a spring 22 arranged to exert pressure against the lug 23 integral with the bottom side of the feeder plate 17. Pressure exerted by the spring 22 holds the roller in contact with the cam 24 integral with the shaft 25. The shaft 25 is journalled in the main frame 10 for rotation (by source of power not shown) whereby the cam 24 is actuated to impart forward movement to the feeder plate 17 and compression to the spring 22. Comparable to the forward movement, a faster backward movement of the feeder plate is effected by the spring 22 maintaining the roller in contact with that portion of the cam 24 which is shaped to provide a comparable faster backward movement. By reason of the rapidity of the backward movement, the feeder plate 17 slips under the

55 coal, while the forward movement of the feeder

plate 71 carries the coal across the machine onto a single endless belt 26 trained over a pulley 27.

The forward end of the base 16 terminates in an inclined portion 28 from which extends a platform consisting of a web 29 between the ribs 30 extending from the main portion of the main frame 10. Integral with the forward end of the ribs 30 are housings 31 and 32 in which is journalled a rotary cutter bar comprising a shaft 33 provided with bits 34, 35, 36 and 37. Integral with the shaft 33 is a sprocket 38. To the rear of and in alignment with the sprocket 38 is a sprocket 39 fixed to a power driven shaft 40 (source of power not shown). A cutter chain 41 in a plane parallel to the side of the main frame 10 is trained over the sprockets 38 and 39 for driving the rotary cutter bar. The rotary cutter bar is operative to undercut and form a kerf in the coal to be mined. The forward sides of the housing 31 and 32 are formed to provide the wedges 42 and 43. Adjacent to the sides of the wedge 43 are bits 34 and 35, the bit 34 being adapted to cut a recess in the coal side face 44 in a plane parallel to the side of the main frame 10 opposite to the cutter chain 41. Adjacent to the sides of the wedge 42 is a bit 37 and a cutter chain 41 carrying teeth 45. The cutter chain teeth 45 are adapted to cut a recess in the coal side face 46 in a plane parallel to the side of the main frame 10. Adjustable shoes 47, secured to the backward underside of the main frame 10, are adapted to bear against the solid side faces 44 and 46 of the recesses cut by the bit 34 and the cutter chain teeth 45 for guiding and holding the machine in alignment.

To the rear of the rotary cutter bar and integral with the underside of the inclined portion 28 is a semi-circular trough 48 with an open side toward the rotary cutter bar. Concentric with the trough 48 is a conveyor screw comprising screw 49 integral with the periphery of the shaft 50 journalled in the ribs 30. Adjacent and parallel to the shaft 50 is a shaft 51 on which the pulley 27 is keyed. Fixed to the shaft 51 is a gear 52 meshed with a gear 53 fixed to the shaft 50. The endless belt 26, trained over the pulley 27, is adapted to impart rotation to the conveyor screw. A pair of spaced upright supporting brackets or bearings 54 is mounted on the main frame 10 and a pair of horizontal shafts 55 and 56 are journalled therein. A pair of guides 57 and 58 is pivotally mounted at their backward ends on the shaft 55. Quadrant gear 59, keyed to the shaft 56, is meshed with the quadrant gear 60 integral with a cross member 61 which is integral with the guides 57 and 58. A second quadrant gear 62, keyed to the shaft 56, is meshed with a rack 63 integral with a piston rod 64, said piston rod 64 being fixed to a piston 65 reciprocally mounted in a carriage swing cylinder 66 secured in the main frame 10. Source of fluid under pressure and means for directing fluid against the piston 65 for swinging the guides 57 and 58 about the shaft 55 will be described.

The guides 57 and 58 are provided with bearing portions 67 and 68 respectively, on which the ram bars 69 and 70 forming the sides of the carriage are slidably mounted. The ram bars 69 and 70 are tied together with a base plate 71 to complete the carriage. The ram bars 69 and 70 are adapted to reciprocate on the bearing portions 67 and 68. Racks 72, integral with the ram bars 69 and 70, are meshed with rack pinions 73, keyed to the shaft 55 for equalizing the movement of the ram bars 69 and 70. Secured to the base 75

plate 71 is a wedge plate 74 with teeth 75, 76 and 77. A cylinder 78 for reciprocating the wedge plate is provided with a yoke 79 integral with the backward end of the cylinder 78. A cross-head 80, slidably mounted in the yoke, is interposed between springs 81 backed against the opposite ends of the yoke 79. A pin 82 extends through the cross-head 80 at right angles to the springs 81 and is journalled at the opposite ends of the pin in a pair of brackets 83 integral with the cross member 61 of the guides 57 and 58. A piston 84 in the cylinder 78 is fixed to a piston rod 85 with a pin 86 journalled in the piston rod head 87. Opposite ends of the pin 86 are secured in a pair of lugs 88 integral with the base plate 71. Source of the fluid under pressure and means for directing said fluid against the piston 84 for reciprocating the wedge plate 74 will now be described.

An injector cylinder 89 is secured to the forward underside of the cylinder 78. The rear end of the injector cylinder has an opening 90. A piston 91 is reciprocally mounted in the injector cylinder 89. A spring 92 is provided for exerting pressure against the piston 91, said spring 92 being adapted to impart forward movement to the piston 91 to a position against the ring 93 whereby fluid is drawn into the injector cylinder 89 through the opening 90. The forward end of the piston 91 is provided with a boss 94 protruding through ring 93. A bracket 95, integral with the piston rod head 87, is provided with an adjustable pin 96 adapted to engage the boss 94, causing fluid in the injector cylinder 89 to be discharged through the opening 90.

The selective valve 97, Figures 3 and 8, has a reciprocable spool 98. A pilot cylinder 99, integral with the selective valve 97, is in alignment with spool 98. A pilot piston 100 in the pilot cylinder 99 is fixed to a stem 101. One end of stem 101, extending through the end of the pilot cylinder 99, is connected with the spool 98, with the opposite end of the stem 101 extending through the opposite end of the pilot cylinder 99. An inlet 102 is provided in the end of the selective valve 97. Openings 103, 104 and 105 in the side of the selective valve 97 are connected with the ports 106, 107 and 108, respectively. Openings 109 and 110 are provided at the opposite ends of the pilot cylinder 99 for flow of fluid into the opposite ends of the pilot cylinder 99. Flow of fluid under pressure into the opposite ends of the pilot cylinder 99, alternately imparts reciprocatory movement to the spool 98. Reciprocatory movement of the spool 98 in relation to the ports 106, 107 and 108 causes fluid to be directed and released through the ports 106, 107 and 108. An auxiliary selective valve 111 has a reciprocable spool 112. A pilot cylinder 113, integral with the auxiliary selective valve 111, is in alignment with the spool 112. A pilot piston 114 in the pilot cylinder 113 is fixed to a stem 115. One end of the stem 115 extends through the end of the pilot cylinder 113 and is connected with the spool 112, with the opposite end of the stem 115 extending through the opposite end of the pilot cylinder 113 at right angles to that portion of the stem 101 extending through the end of the pilot cylinder 99. The end portion of the stem 115 is adapted to move into the path of the end portion of the stem 101 for the purpose to be described. An inlet 116 is provided in the end of the auxiliary selective valve 111. Openings 117, 118 and 119 in the sides of the auxiliary selective valve 111 are connected with the ports 120, 121 and

122, respectively. Openings 123 and 124 are provided at the opposite ends of the pilot cylinder 113 for flow of fluid into the pilot cylinder 113. Flow of fluid under pressure into the opposite ends of the pilot cylinder 113 alternately imparts reciprocatory movement to the spool 112. Reciprocatory movement of the spool 112 in relation to the ports 120, 121 and 122 causes fluid to be directed and released through the ports 120, 121 and 122.

The relief valve 125 has a reciprocable spool 126. A spring 127, seated in the spool 126, exerts pressure against the spool. A plunger 128 is integral with the spool 126, said plunger being adapted to extend into the bore 129 of the relief valve 125. An inlet 130 and an outlet 131 are provided in the opposite sides of the relief valve with a duct 132 extending from the inlet 130 to the bore 129. Fluid flowing through the relief valve, exceeding the working pressure, causes the plunger 128 to exert sufficient pressure against the spring 127 to actuate the spool 126 whereby the spool is positioned in relation to the relief opening 133 for release of the fluid.

The pressure valve 134 has a reciprocable plunger 135 with an orifice 136. A seat 137 is provided in the pressure valve 134 for seating the plunger 135, said plunger having a spring 138 seated therein for exerting pressure against the plunger. An inlet 139 is located in the pressure valve adjacent to the end of plunger 135. An outlet 140 is provided in the side of the pressure valve, which is normally closed. Flow of fluid through the inlet 139 imparts movement to the plunger 135 whereby the outlet 140 is opened for flow of fluid through the pressure valve 134. The orifice extends longitudinally through the center of the plunger 135 and serves to bypass the fluid to permit the plunger 135 to seat after flow of the fluid through the pressure valve 134 is cut off. The orifice 136 is an opening of specific area to cause an elapse of time for bypass of the fluid to seat the plunger 135, whereby the fluid under pressure is retained in the pressure valve 134 for a predetermined time interval.

The check valve 141 has a plunger 142 and is provided with a seat 143 for seating said plunger 142. A spring 144 is located in the plunger 142 for normally holding the plunger on the seat 143. Inlet 145 is provided in the end of the check valve adjacent to the seated end of the plunger 142 and outlet 146 is located in the side of the check valve, said outlet 146 being cut off from the inlet 145 when the plunger 142 is seated.

The control valve 147 has a reciprocable plug 148. A passage 149 extends longitudinally through the center of the plug 148 for providing fluid at both ends of the plug. A stem 150 is fixed to the plug 148 for manually actuating the plug. An inlet 151 is provided in the end of the control valve. Outlets 152 and 153 in sides of the control valve are connected with the ports 154 and 155, respectively. The plug 148 is adapted to open the ports 154 and 155 alternately. Mounted on the main frame 10 is a tank 156 for providing a supply of fluid (preferably oil). A pump 158 is also mounted on the main frame 10 and is provided with a suction line 157 connected to the tank 156 and a discharge line 159 connected to the control valve 147.

In operation the main frame 10 is fed forwardly on the skid base 11 by directing fluid under pressure against the piston 13 reciprocally mounted in the skid base cylinder 12 (source of fluid not shown). Forward movement of the

main frame 10 engages the rotary cutter bar bits 34, 35, 36 and 37, wedge portions 42 and 43 of the cutter bar housings 31 and 32, and the cutter chain teeth 45 with the coal to be mined. The bits 34 and 35 cut away the coal adjacent the wedge 43, while the bit 37 and the cutter chain teeth 45 cut away the coal adjacent the wedge 42. The wedges 42 and 43 penetrate and crowd the coal at the forward side of the housings 31 and 32 into the kerf cut adjacent to the wedges and the coal thus crowded into the kerfs is accordingly brushed rearwardly by the bits 34, 35, 36 and 37, and the cutter chain teeth 45, thereby providing space for advancing the housings 31 and 32. Cuttings from the rotary cutter bar are shrouded by the web 29 and pushed back into the semi-circular trough 48, the conveyor screw 49 being concentrically mounted in the trough 48 for conveying the cuttings onto belt 26.

20 Mounted in the guides 57 and 58 is a carriage carrying a wedge plate 74, the carriage being geared for reciprocatory and vertical movement. Forward movement of the carriage drives the wedge plate into the coal face undercut by the 25 rotary cutter bar. At the end of each backward movement of the carriage the same is elevated for wedging off a successive portion of coal to a predetermined height, after which the carriage is lowered to position the wedge plate immediately above the kerf. Coal wedged from the coal face above a kerf falls to the platform, 30 consisting of the web 29 between the ribs 30. By reason of the platform entering the kerf being cut, the coal resting on the platform and backed by that portion of the coal face to be 35 mined above the kerf is crowded from the platform onto the feeder plate 17 and the endless conveyor belt 26. Successive portions of coal wedged from the coal face flow on to the feeder plate 17 and to the endless conveyor belt 26. Top 40 sides 160 of the housing 31 and 32 bear against the top side of the undercut, which provides backing at the forward end of the main frame 10 for resisting the upward reactive force exerted, thereby driving the wedge plate 74 into the coal. Adjustable shoes 47, secured to the 45 backward underside of the main frame 10, bear against the solid side faces 44 and 46 of the recess cut in the coal by the bit 34 and the cutter chain teeth 45. The adjustable shoes 47, backed by the 50 solid side faces 44 and 46, serve to hold the wedge portions 42 and 43 of the cutter bar housings 31 and 32 in proper alignment for guiding the machine in the path of the coal to be mined when fed forwardly on the skid base 11.

55 In carrying out the operation of the apparatus for imparting reciprocatory movement to the wedge plate, the power driven pump 158 (source of power not shown) is adapted to draw fluid from the tank 156 through the line 157 and discharge said fluid under pressure through the line 159 provided with the manually operated control valve 147. The control valve 147 is adapted to direct the fluid through the line 161 to the selective valve 97 or through line 162 to the tank 156. The spool 98, as shown is positioned in relation to the ports 106, 107 and 108 for release of fluid from the backward end of the cylinder 78 through the line 163, simultaneously directing the fluid through the line 164 to the forward end of cylinder 78, causing the wedge plate 74 to be retracted with the piston 84 at the end of the stroke. By reason of the piston 84 coming to a state of rest at the end of the backward stroke, 60 the pressure in line 164 exceeds the working pres-

sure, causing the fluid to escape from the relief valve 125 provided in line 164. Fluid escaping from relief valve 125 in the line 164, flows through the tank return line 165 having pressure valve 134. Fluid flowing through the pressure valve 134 in the line 165 causes movement of plunger 135 against the spring 138. Pressure required to move the plunger 135 against spring 138 is diverted through the line 166 to the opening 109 in pilot cylinder 99. Pressure diverted into the pilot cylinder 99 causes pilot piston 100 to position the spool 98 in relation to ports 106, 107 and 108 for directing fluid through line 163 to the backward end of cylinder 78, simultaneously releasing the fluid through the line 164 from the forward end of the cylinder 78, thereby causing piston 84 to move the wedge plate 74 forwardly to the end of the stroke. By reason of piston 84 coming to a state of rest at the end of the forward stroke, pressure in the line 163 exceeds the working pressure, thereby causing the fluid to escape from the relief valve 125 provided in the line 163. Fluid escaping from relief valve 125 in the line 163 flows through the tank return line 167 having the pressure valve 134. Fluid flowing through pressure valve 134 in the line 167 causes movement of the plunger 135 against the spring 138. Pressure required to move the plunger 135 against the spring 138 is diverted through the line 168 to the opening 110 in the pilot cylinder 99. Pressure diverted into the pilot cylinder 99 causes the pilot piston 100 to position the spool 98 in relation to the ports 106, 107 and 108 for directing the fluid to the backward end of cylinder 78 through line 163, and simultaneously releasing the fluid through the line 164 from the forward end of cylinder 78, thereby causing the piston 84 to again move the wedge plate 74 forwardly.

The crosshead 80 being connected to the carriage guides 51 and 58 and interposed between the springs 81, seated in the opposite ends of the yoke 79 integral with cylinder 78, provides a resilient connection to the cylinder. The cylinder 78 is adapted to yield in relation to the piston 84 to provide space between the end of the cylinder and the end of the piston for absorbing excess volume of fluid directed into the cylinder and thereby absorb the shock imposed to accelerate the wedge plate 74. By reason of the resilient connection absorbing the shock imposed to accelerate the wedge plate 74, the working pressure of the fluid directed into the cylinder 74 is not exceeded. The resilient connection to the cylinder 78 also serves to decelerate the wedge plate 74 when the piston 84 abuts either end of the cylinder.

In carrying out the operation of the apparatus for imparting swinging movement to the plate 74, the injector cylinder 89 is fixed to the forward underside of the cylinder 78. Said injector cylinder 89 is provided with a piston 91 and a spring 92. The spring 92 is adapted to exert pressure against the piston 91 for normally maintaining the piston 91 against the ring 93 fixed to the forward end of the injector cylinder 89. A boss 94, located on the forward end of the piston 91, protrudes through the ring 93. A bracket 95 is integral with the piston rod head 87, said bracket being provided with an adjustable pin adapted to engage the boss 94. A swing cylinder 66 is mounted in the main frame 19 and is provided with a piston 65 fixed to a piston rod 64. The piston rod 64 is provided with a rack 63 meshed with a quadrant gear 62 keyed on the shaft 56.

A second quadrant gear 59, keyed on the shaft 56, is meshed with the quadrant gear 60 integral with the cross member 61 of the guides 57 and 58. The line 169, having a relief valve 125, connects the injector cylinder 89 to the forward end of the swing cylinder 66. The line 169 is connected to the tank line 162, with the line 170 being provided with the check valve 141. Fluid is drawn into the injector cylinder 89 from the line 162 through the lines 170 and 169 by reason of the forward movement imparted to the injector piston 91 by the spring 92. The check valve 141 in the line 170 is adapted to prevent the return of the fluid from the injector cylinder 89 to the tank 156. Engagement of the adjustable pin 96 with the boss 94 on the injector piston 91 imparts backward movement to the injector piston, causing a predetermined amount of fluid under pressure to flow through the line 169 into the forward end of the swing cylinder 66. A predetermined amount of fluid, directed into the swing cylinder 66, imparts a specific amount of movement to the piston 65 whereby the rack 63, meshing with the quadrant gear 62, causes the carriage to swing a step upward to position the wedge plate 74 for the successive forward stroke of the wedge plate. On the completion of a predetermined number of upward steps of the wedge plate 74, the end of the rack 63 engages an adjustable stop 171. At the time the end of the rack 63 engages the adjustable stop 171, the fluid pressure in the line 169 exceeds the working pressure, causing the fluid to escape from the relief valve 125 provided in line 169. Fluid escaping from the relief valve 125 in line 169 flows through the tank return line 172 having a pressure valve 134. Fluid flowing through the pressure valve 134 in line 172 causes movement of the plunger 135 against the spring 138. Pressure required to move the plunger 135 against the spring 138 is diverted through the line 173 to the opening 124 in the pilot cylinder 113. Pressure diverted into the pilot cylinder 113 causes the pilot piston 114 to position the spool in relation to the ports 120, 121 and 122 in the auxiliary selective valve 111 for directing the fluid under pressure from line 175 and through line 176 to the backward end of the swing cylinder 66, simultaneously releasing the fluid through the lines 174 and 169 from the forward end of the swing cylinder 66 and causing forward movement of the piston 65 to the end of the stroke. The spool 112 is positioned for directing the fluid to the backward end of the swing cylinder 66 thus simultaneously releasing the fluid from the forward end of the swing cylinder 66. The end portion of the stem 115 moves into the path of the end portion of the stem 101, causing the spool 98 to be latched against movement whereby the reciprocating movement of the wedge plate 74 is stopped in retracted position to clear the material to be mined when the wedge plate is being swung to the bottom position. By reason of the swing cylinder piston 65 coming to a state of rest at the end of the forward stroke, the pressure in the line 176 exceeds the working pressure, causing the fluid to escape from the relief valve 125 provided in the line 176. Fluid escaping from relief valve 125 in line 176 flows through the tank return line 177 having a pressure valve 134. Fluid flowing through the pressure valve 134 causes movement of the plunger 135 against the spring 138. The pressure required to move the plunger 135 against the spring 138 is diverted through line 178 to the opening 123 in the pilot cylinder 113. Pressure diverted into the pilot

cylinder 113 causes the pilot piston 114 to position the spool 112 in relation to the ports 120, 121 and 122 in the auxiliary selective valve 111 for releasing the fluid through the line 176 from the backward end of the swing cylinder 66 and simultaneously cutting off release of the fluid from the forward end of the swing cylinder. The spool 112 being positioned for releasing the fluid from the backward end of the swing cylinder 66 and with the release of the fluid from the forward end of the swing cylinder 66 being cut off, the end portion of the stem 115 is withdrawn from the path of the end portion of the stem 101 whereby the spool 98 is free to be actuated for reciprocating the wedge plate as described.

A machine as described above is particularly adapted for continuous operation, that does not require removal of the machine or a plurality of machines from the respective working faces.

I claim:

1. In a mining machine having a main frame, guides mounted for vertical swinging movement relative to said main frame, a carriage reciprocally mounted in said guides, a dislodging member mounted on said carriage, means to reciprocate said carriage for driving said dislodging member into the material to be mined comprising a main cylinder anchored to said guides, a piston reciprocally mounted in said main cylinder and connected to said dislodging member, a main selective valve provided with ports, a spool reciprocally mounted in said main selective valve, a pilot cylinder adjacent said main selective valve, a pilot piston reciprocally mounted in said pilot cylinder having a stem connected to said spool, means for providing fluid under pressure to said main selective valve, means for actuating said pilot piston for positioning said spool in relation to said ports in said main selective valve for directing and releasing fluid to and from opposite ends of said main cylinder alternately whereby reciprocatory movement is imparted to said wedge plate, means for absorbing the shock imposed to accelerate and decelerate said dislodging member at end of stroke, means for swinging said dislodging member upwardly in steps to position said dislodging member for breaking down successive portions of the material to be mined, means for rendering said dislodging member inoperative in retracted position to clear said dislodging member of the material to be mined when said dislodging member is being swung downwardly, and means for swinging said dislodging member downwardly to bottom position.

2. In a mining machine having a main frame, guides mounted for vertical swinging movement relative to said main frame, a carriage reciprocally mounted in said guides, a transverse wedge plate mounted on said carriage, a main cylinder anchored to said guides, a piston reciprocally mounted in said main cylinder connected to said carriage, a main selective valve provided with ports, a spool reciprocally mounted in said main selective valve, a pilot cylinder adjacent said main selective valve, a pilot piston reciprocally mounted in said pilot cylinder, said pilot piston having a stem connected to said spool, means for actuating said pilot piston for positioning said spool in relation to said ports for directing and releasing fluid to and from opposite ends of said main cylinder alternately to impart reciprocatory movement to said wedge plate for driving said wedge plate into the material to be mined comprising a relief valve at opposite ends of said main cylinder adapted to release fluid exceeding the working pressure at the end of each stroke of said

piston, a pressure valve connected to each of said relief valves, said pressure valve consisting of a body, a seat provided in said body, a plunger reciprocally mounted in said body, an orifice longitudinally through said plunger, a spring exerting pressure against said plunger for normally holding said plunger to said seat, an outlet in side of said body, fluid escaping momentarily from said relief valve enters said body through said inlet imparting movement to said plunger whereby said outlet is opened for flow of fluid through said body, on recession of the flow of fluid through said body said plunger closes said outlet by reason of said spring imparting movement to said plunger and thereby trapping fluid under pressure in said body, fluid trapped in said body is gradually released through said orifice in said plunger for a predetermined time interval and thereby diverting pressure for a predetermined time interval to said pilot cylinder whereby said pilot piston is actuated for positioning said spool in relation to said ports.

3. In a mining machine having a main frame, guides mounted for a vertical swinging movement relative to said main frame, a carriage reciprocally mounted in said guides, a dislodging member mounted on said carriage, a main cylinder anchored to said guides, a piston reciprocally mounted in said main cylinder connected to said dislodging member, a main selective valve provided with ports, a spool reciprocally mounted in said main selective valve, a pilot cylinder adjacent said main selective valve, a pilot piston reciprocally mounted in said pilot cylinder having a stem connected to said spool adapted to be actuated for positioning said spool in relation to said ports whereby fluid is directed and released to and from opposite ends of said main cylinder alternately to impart reciprocatory movement to said dislodging member for driving said dislodging member into the material to be mined, means for diverting fluid under pressure to opposite ends of said pilot cylinder alternately for actuating said pilot piston comprising a relief valve connected to each end of said main cylinder, a pressure valve connected to each of said relief valves, fluid directed to opposite ends of said main cylinder alternately exceeds the working pressure at end of each stroke of said piston causing fluid to escape from said relief valves alternately, fluid escaping from said relief valves flows through said pressure valves alternately, said pressure valves being adapted to divert fluid under pressure to opposite ends of said pilot cylinder alternately for actuating said pilot piston.

4. In a mining machine having a main frame, guides mounted for vertical swinging movement relative to said main frame, a carriage reciprocally mounted in said guides, a transverse wedge plate mounted on said carriage, a main cylinder anchored to said guides, a piston reciprocally mounted in said main cylinder having a piston rod with a piston rod head connected to said carriage, a tank containing fluid, means for directing and releasing fluid to and from opposite ends of said main cylinder alternately to impart reciprocatory movement to said wedge plate, means for swinging said wedge plate in steps whereby said wedge plate is positioned for breaking down successive portions of material to be mined comprising a swing cylinder having a piston rod geared to said guides, an injector cylinder fixed to said main cylinder, a fluid line provided with a check valve connecting said injector cylinder with said tank, a fluid line connecting said injector cylinder with said swing cylinder, an in-

jector piston reciprocally mounted in said injector cylinder adapted to draw fluid from said tank into said injector cylinder through said fluid line provided with said check valve, said check valve being adapted to trap fluid in said injector cylinder, an adjustable pin fixed to said piston rod head adapted to engage and impart movement to said injector piston causing a predetermined amount of fluid to be forced through said fluid line from said injector cylinder to said swing cylinder whereby a predetermined amount movement is imparted to said swing piston for positioning said wedge plate for breaking down successive portions of material to be mined.

5. In a mining machine having a main frame, guides mounted for vertical swinging movement relative to said main frame, a carriage reciprocally mounted in said guides, a wedge plate mounted on said carriage, means for reciprocating said carriage for driving said wedge plate into the material to be mined, means for swinging said wedge plate in steps for breaking down successive portions of material to be mined comprising a swing cylinder mounted in said main frame, a swing piston reciprocally mounted in said swing cylinder, said swing piston being fixed to a piston rod geared to said guides, means for injecting successive predetermined amounts of fluid into said swing cylinder causing successive movements of said swing piston for swinging said wedge plate in steps whereby said wedge plate breaks down successive portions of material to be mined.

6. In a mining machine having a main frame, guides mounted for vertical swinging movement relative to said main frame, a carriage reciprocally mounted in said guides, a transverse wedge plate mounted on said carriage, a main cylinder anchored to said guides, a piston reciprocally mounted in said main cylinder having a piston rod with a piston rod head connected to said wedge plate, a tank containing fluid, means for directing and releasing fluid to and from opposite ends of said main cylinder alternately to impart reciprocatory movement to said wedge plate for driving said wedge plate into the material to be mined, means for swinging said wedge plate downwardly from a predetermined height to bottom position comprising a swing cylinder mounted in said main frame, a swing piston reciprocally mounted in said swing cylinder having a piston rod geared to said guides, an auxiliary selective valve, a pilot cylinder adjacent said auxiliary selective valve, a pilot piston reciprocally mounted in said pilot cylinder having a stem fixed to a spool reciprocally mounted in said auxiliary selective valve, a port in said auxiliary selective valve, a fluid line connecting said port to the forward end of said swing cylinder, a second port in said auxiliary selective valve, a fluid line provided with a relief valve connecting said second named port to backward end of said swing cylinder, a third port in said auxiliary selective valve, a fluid line connecting said third named port with said tank, said spool being positioned in said auxiliary selective valve to release fluid from the backward end of said swing cylinder and to cut off flow of fluid from the forward end of said swing cylinder to said tank, an injector cylinder fixed to said main cylinder, a fluid line provided with a check valve connecting said injector cylinder with said tank, a fluid line provided with a relief valve connecting said injector cylinder with the forward end of said swing cylinder, an injector piston reciprocally mounted in said injector cylinder adapted to draw fluid from said tank into said injector cylinder through said

line provided with said check valve, said check valve being adapted to trap fluid drawn into said injector cylinder, an adjustable pin fixed to said piston rod head being adapted to engage and impart movement to said injector piston to force fluid into the forward end of said swing cylinder for imparting movement to said swing piston, and whereby said swing piston rod engages an adjustable stop fixed to said main frame, said swing piston rod engaging said adjustable stop causes said swing piston to come to state of rest whereby the working pressure is exceeded causing fluid to escape from said relief valve provided in said fluid line connecting said injector cylinder to the forward end of said swing cylinder, fluid escaping from said relief valve provided in said fluid line connecting said injector cylinder to the forward end of said swing cylinder is diverted under pressure into said pilot cylinder to impart movement to said pilot piston for positioning said spool in relation to said ports in said auxiliary selective valve for releasing fluid from the forward end of said swing cylinder and for directing fluid to the backward end of said swing cylinder whereby movement is imparted to said swing cylinder piston to end of the stroke and whereby said wedge plate is swing downwardly to bottom position.

7. In a mining machine having a main frame, guides mounted for vertical swinging movement relative to said main frame, a carriage reciprocally mounted in said guides, a wedge plate mounted on said carriage, means for reciprocating said carriage for driving said wedge plate into the material to be mined, means for swinging said wedge plate in steps to position said wedge plate for breaking down successive portions of material to be mined to a predetermined height, means for swinging said wedge plate to bottom position comprising a swing cylinder mounted in said main frame, a swing piston reciprocally mounted in said swing cylinder, said swing piston being fixed to a piston rod geared with said guides, means for directing fluid into said swing cylinder to impart movement to said swing piston whereby said wedge plate is swung to bottom position.

8. In a mining machine having a main frame, guides mounted for vertical swinging movement relative to said main frame, a carriage reciprocally mounted in said guides, a transverse wedge plate mounted on said carriage, a main cylinder anchored to said guides, a piston reciprocally mounted in said main cylinder connected to said wedge plate, a swing cylinder mounted in said main frame, a swing piston reciprocally mounted in said swing cylinder fixed to a piston rod geared to said guides, a main selective valve provided with ports, a spool reciprocally mounted in said main selective valve, a pilot cylinder adjacent said main selective valve, a pilot piston reciprocally mounted in said pilot cylinder, said pilot piston having a stem, one end of said stem being connected to said spool with opposite end of said stem extending through end of said pilot cylinder, means for diverting fluid under pressure to said pilot cylinder for positioning said spool in relation to said ports whereby fluid is directed and released to and from opposite ends of said main cylinder alternately to impart reciprocatory movement to said wedge plate for driving said wedge plate into the material to be mined, an auxiliary selective valve provided with ports, a spool reciprocally mounted in said auxiliary selective valve, a pilot cylinder adjacent said auxiliary selective valve, a

13

pilot piston having a stem reciprocally mounted in said pilot cylinder adjacent said auxiliary selective valve, one end of said stem being connected to said spool in said auxiliary selective valve with opposite end of said stem extending through end of said pilot cylinder adjacent said auxiliary selective valve, means for diverting fluid under pressure to said pilot cylinder adjacent said auxiliary selective valve for positioning said spool in said auxiliary selective valve in relation to said ports in said auxiliary selective valve whereby fluid is directed to and released from said swing cylinder for imparting movement to said piston rod for swinging said wedge plate downwardly to bottom position, means for rendering said wedge plate inoperative in retracted position to clear the material to be mined when said wedge plate is being swung downwardly to bottom position comprising portion of said stem extending through end of said pilot cylinder adjacent said auxiliary selective valve being adapted to move into the path of the portion of said stem extending through end of said pilot cylinder adjacent said main selective valve whereby said main selective valve is held inoperative causing said wedge plate to cease reciprocatory movement in retracted position when said wedge plate is being swung downwardly to bottom position.

9. In a mining machine having a main frame, guides mounted for vertical swinging movement relative to said main frame, a carriage reciprocally mounted in said guides, a wedge plate mounted on said carriage, a main cylinder anchored to said guides, a main piston reciprocally mounted in said main cylinder connected to said wedge plate, a swing cylinder mounted in said main frame, a swing piston reciprocally mounted in said swing cylinder, said swing piston being fixed to a piston rod geared to said guides, a main selective valve provided with ports, a spool reciprocally mounted in said main selective valve, a stem fixed to said spool reciprocally mounted in said main selective valve, means for positioning said spool in relation to said port in said main selective valve whereby fluid is directed and released to and from the opposite ends of said main cylinder alternately to impart reciprocatory movement to said wedge plate for driving said wedge plate into material to be mined, an auxiliary selective valve provided with ports, a spool reciprocally mounted in said auxiliary selective valve, a stem fixed to said spool reciprocally mounted in said auxiliary selective valve, means for positioning said spool in relation to said ports in said auxiliary selective valve whereby fluid is directed to said swing cylinder for imparting movement to said piston rod for swinging said wedge plate to bottom position, means for stopping the reciprocatory movement of said wedge plate in retracted position to clear the material to be mined when said wedge plate is being swung to bottom position comprising said stem fixed to said spool reciprocally mounted in said auxiliary selective valve being adapted to move into the path of said stem fixed to said spool reciprocally mounted in said main selective valve whereby said main selective valve is held inoperative causing the reciprocatory movement of said wedge plate to be stopped in retracted position when said wedge plate is being swung to bottom position.

10. In a mining machine having a main frame, guides mounted for vertical swinging movement relative to said main frame, a carriage reciprocally mounted in said guides, a dislodging

14

member mounted on said carriage, means for reciprocating said dislodging member for driving said dislodging member into the material to be mined, a swing cylinder mounted in said main frame, a swing piston reciprocally mounted in said swing cylinder having a piston rod geared to said guides, an auxiliary selective valve provided with ports, a spool reciprocally mounted in said auxiliary selective valve, a pilot cylinder adjacent said auxiliary selective valve, a pilot piston in said pilot cylinder having a stem connected to said spool and adapted to be actuated for positioning said spool in relation to said ports for directing and releasing fluid to and from opposite ends of said swing cylinder alternately for imparting upwardly and downwardly swinging movement to said dislodging member whereby said dislodging member is positioned for breaking down successive portions of the material to be mined, means for actuating said pilot piston to position said spool in relation to said ports in said auxiliary selective valve comprising a relief valve connected to opposite ends of said swing cylinder, fluid directed into opposite ends of said swing cylinder alternately exceeds the working pressure at the end of each stroke of said swing piston causing fluid to escape from said relief valves alternately, fluid escaping from said relief valves is diverted under pressure into opposite ends of said pilot cylinder alternately whereby said pilot piston is actuated for positioning said spool in relation to said ports in said auxiliary selective valve.

11. In a mining machine, in combination, a main frame, a wedge plate mounted by the frame for reciprocating movement relative thereto, motor means for reciprocating said wedge plate to break down the material to be mined, said motor means including a cylinder, a piston mounted for movement in the cylinder and operatively connected to the wedge plate, selective valve means having connection with a source of fluid under pressure, fluid conducting means respectively connecting the selective valve means with opposite ends of the cylinder for alternately delivering pressure fluid to and venting said fluid from respective ends of the cylinder as determined by the selective valve means, whereby reciprocating movement is imparted to the piston and thus to the wedge plate, the said pressure fluid being delivered to the cylinder momentarily attaining an excessive pressure such as to exceed the working pressure at the end of each stroke of the piston, and control means responsive to said excessive pressure at the end of each stroke of the piston and operative to actuate the selective valve means to reverse the flow of pressure fluid, whereby pressure fluid is delivered to that end of the cylinder previously vented and the opposite end is vented to cause a return stroke of the piston.

12. A mining machine as defined by claim 11, wherein the selective valve means includes a spool adapted to be reciprocated for directing the pressure fluid to and releasing the pressure fluid from respective ends of the cylinder, a pilot cylinder having a pilot piston connected to the spool for reciprocating the same, and wherein said control means includes a relief valve interposed in the conducting means respectively, and other conducting means connecting each said relief valve with one end of the pilot cylinder.

13. In a mining machine, in combination, a main frame, a wedge plate mounted by the frame for reciprocating movement relative thereto, motor means for reciprocating said wedge plate to break down the material to be mined, said motor

means including a cylinder, a piston mounted for movement in the cylinder and operatively connected to the wedge plate, selective valve means having connection with a source of fluid under pressure, fluid conducting means respectively connecting the selective valve means with opposite ends of the cylinder for alternately delivering pressure fluid to and venting said fluid from respective ends of the cylinder as determined by the selective valve means, whereby reciprocating movement is imparted to the piston and thus to the wedge plate, the said pressure fluid delivered to the cylinder momentarily attaining an excessive pressure such as to exceed the working pressure at the end of each stroke of the piston, control means responsive to said excessive pressure at the end of each stroke of the piston and operative to actuate the selective valve means to reverse the flow of pressure fluid, whereby pressure fluid is delivered to that end of the cylinder previously vented and the opposite end is vented to cause a return stroke of the piston, and means resiliently connecting the cylinder to the said main frame to permit movement of the cylinder in either direction against the tension of said resilient means and to a limited extent with respect to the piston, whereby to provide space for absorbing pressure fluid delivered to the cylinder sufficient to prevent the occurrence of an excessive pressure exceeding the working pressure except at the end of each stroke of the piston.

14. A mining machine as defined by claim 13, wherein the means resiliently connecting the cylinder to said main frame includes a yoke extending rearwardly from the end wall of the cylinder, a crosshead slidably mounted in the yoke, resilient means on each side of the crosshead between the same and the yoke, and a member extending through the crosshead at right angles to its direction of movement and fixed at respective ends.

15. In a mining machine, in combination, a main frame, guides mounted on a horizontal axis provided by the main frame for vertical swinging movement with respect to the frame, a carriage reciprocally mounted in said guides, a wedge plate fixed to the carriage, first motor means for reciprocating the carriage and thus the wedge plate to break down the material to be mined, second motor means for imparting swinging movement to the guides and thus the wedge plate to cause the same to vertically traverse the face of the material to be mined, said first motor means including a first cylinder and a piston mounted for movement in the cylinder and connected to the carriage, said second motor means including a second cylinder and a piston mounted for movement in the cylinder and operatively connected to the guides, selective valve means for each cylinder and each selective valve means having connection with a source of fluid under pressure, fluid conducting means for the cylinders respectively each having connection with a selective valve means and connecting the same to opposite ends of its cylinder for alternately delivering pressure fluid to and venting said fluid from respective ends of its cylinder as determined by its selective valve means, whereby reciprocating movement is imparted to the pistons of said cylinders to reciprocate the wedge plate and cause swinging movement of the guides, the said pressure fluid being delivered to the cylinders momentarily attaining an excessive pressure such as to exceed the working pressure at the end of each stroke of its piston, and control means for each selective valve means re-

sponsive to the excessive pressure at the end of each stroke of its piston and operative to actuate the selective valve means to reverse the flow of pressure fluid, whereby pressure fluid is delivered to that end of each cylinder previously vented and the opposite end is vented to cause a return stroke of the pistons respectively.

16. A mining machine as defined by claim 15, wherein the selective valve means for the cylinders respectively have interlocking relation with each other when in certain positions, whereby when the selective valve means for the second cylinder is positioned to effect flow of pressure fluid through the fluid conducting means to cause downward swinging movement of the guides the selective valve means for the first cylinder is locked preventing actuation and maintaining the wedge plate in retracted position.

20 17. In a mining machine, in combination, a main frame, guides mounted on a horizontal axis provided by the main frame for vertical swinging movement with respect to the frame, a carriage reciprocally mounted in said guides, a wedge plate fixed to the carriage, first motor means for reciprocating the carriage and thus the wedge plate to break down the material to be mined as a result of forward reciprocating strokes of the wedge plate, second motor means for imparting swinging movement to the guides and thus to the wedge plate to cause the same to vertically traverse the face of the material to be mined, said second motor means including a swing cylinder and a piston mounted for movement in the cylinder and operatively connected to the guides, a tank containing a fluid adapted to be supplied under pressure to respective ends of the swing cylinder for actuating the piston, an injector cylinder having an injector piston, spring means backing the injector piston to maintain the same in forward position within its cylinder, means fixed to the wedge plate and adapted to contact the injector piston upon each retracted stroke of the wedge plate to move the injector piston rearwardly, whereby the injector piston has pumping action as the wedge plate reciprocates, fluid conducting means having a check valve interposed therein and connecting the injector cylinder with said tank, and other fluid conducting means connecting the said check valve with that end of the swing cylinder to cause upward swinging movement of the guides, whereby the pumping action of the injector piston draws fluid from the tank and delivers the same under pressure to the swing cylinder to cause upward swinging movement of the guides in successive steps alternating with forward reciprocating strokes of the wedge plate.

18. In a mining machine, in combination, a main frame, a wedge plate mounted by the main frame for reciprocation to break down the material to be mined and for vertical swinging movement to cause the wedge plate to traverse the material to be mined, means for reciprocating the wedge plate, motor means for imparting swinging movement to the wedge plate including a swing cylinder and a piston mounted for movement in the cylinder and operatively connected to effect swinging movement of the wedge plate, injector mechanism adapted to be actuated by each retracted stroke of the wedge plate to effect a pumping action of the injector mechanism, a fluid supply tank, and fluid conducting means connecting the injector mechanism with the tank and with that end of the swing cylinder to cause upward swinging movement of the wedge plate,

said injector mechanism and fluid conducting means being constructed and arranged whereby the pumping action of the injector mechanism draws fluid from the tank and delivers the same under pressure to the swing cylinder to cause upward swinging movement of the wedge plate in successive steps.

19. In a mining machine, in combination, a main frame, guides mounted for vertical swinging movement on a horizontal axis provided by the main frame, a carriage reciprocally mounted in said guides, a wedge plate fixed to the carriage, means for reciprocating the carriage and thus the wedge plate comprising a first cylinder and a piston therein mounted for reciprocating movement and connected to the carriage, means resiliently connecting the cylinder to the guides including a yoke extending rearwardly from the end wall of the cylinder, a crosshead slidably mounted in the yoke, resilient means on each side of the crosshead between the same and the

5 yoke, and a member extending through the cross-head at right angles to its direction of movement and fixed at respective ends to the guides, and motor means for imparting swinging movement to the guides including a swing cylinder fixed to the main frame, and a piston mounted for reciprocation in the swing cylinder and operatively connected to the guides.
